UNITED STATES PATENT OFFICE.

EDWARD E. ROSS, OF WILKINSBURG, PENNSYLVANIA.

RESILIENT DEVICE.

1,378,281.

Specification of Letters Patent. Patented May 17, 1921.

Application filed March 21, 1916. Serial No. 85,578.

To all whom it may concern:

Be it known that I, EDWARD E. Ross, a citizen of the United States, residing at Wilkinsburg, in the county of Allegheny and State of Pennsylvania, have invented a certain new and useful Improvement in Resilient Devices, of which the following is a specification.

My invention relates to resilient devices 10 and particularly to resilient devices in which both air and a liquid are used for producing the resiliency.

The object of my invention is to provide a cheap, simple and efficient form of resilient 15 device for use between moving members, such, for example as a pneumatic spring for use on power driven vehicles such as motor cars. Another object of my invention is to provide a resilient device in which air is 20 compressed in an auxiliary chamber for supplying the main cushioning chamber.

My invention consists, generally stated, in the novel arrangement, construction and combination of parts as hereinafter more 25 specifically set forth and described and particularly pointed out in the claims.

To enable others skilled in the art to which my invention appertains to construct, use and install my improved resilient device, 30 I will explain the same more fully referring to the accompanying drawing, in which:—

Figure 1 is a vertical sectional view of one form of device embodying my invention.

Fig. 2 is another form of device showing 35 my invention.

Fig. 3 is a modified method of supplying air to the top of the cylinder.

Like symbols of reference herein indicate 40 like parts in each of the figures of the drawing.

As illustrated in Fig. 1 of the drawing I have shown a U tube apparatus in order to illustrate my invention but I do not limit myself to any particular form or shape as 45 the principle of my invention may be embodied in many different designs such, for instance as in Fig. 2 where I employ a separate chamber 4'.

Considering Fig. 1 the cylinder 1 is provided 50 with a piston 2 which operates therein and such piston is provided with the usual piston rod 3 for operating the same. The cylinder 1 is provided with an annular chamber 4, the purpose of which is herein-

after explained. The cylinder 1 and chamber 4 are closed at their outer ends with a cap 5 while said cylinder is closed at its inner end with a cap 6 which is provided with a bearing 7 in which the piston rod 3 is adapted to operate. The device is provided with brackets 8 for mounting the same in position for operation, but these will vary in shape and size depending upon the use for which the device is intended. The inner wall 9 of the U tube forming the cylinder 1 is provided with a series of ports 10 at the lower end of the same, and such ports decrease in width toward their lower extremities, *i. e.*, the cross-sectional area of each port decreases toward the outer end of the cylinder. The piston 2 is secured to the piston rod 3 in any suitable manner such as by threads 11 and the outer face of said piston is provided with a small boss 12 through which the piston rod 3 extends and a pin 13 passes through said piston rod and boss 12 to prevent said piston from turning. The inner side of the piston 2 is concave or cup shaped in order to provide the well 14 as later explained, while said piston is also preferably provided with the usual piston rings 15. At a point near the upper end of the well 14 the piston rod 3 has a passageway 15' extending through the same and such passageway is connected by a passageway 16 leading to a check valve 17 while the spring 18 of such valve rests upon and is supported by the pin 13. A spiral spring 19 lies between the outer face of the piston 2 and within the recess 5' in the cap 5 to hold the piston in its raised position under steady load conditions.

The annular chamber 4 may be provided with an ordinary admission valve 20 for admitting air into said chamber as required, while the cap 6 may be provided with a valve 21 for admitting air above the piston 2 in the cylinder 1 when said piston is in a lowered position.

The operation of my improved resilient device is as follows:—

Taking for example the application of my invention to a motor vehicle, and considering the necessary connections having been made, air in a compressed state fills the upper end of the annular chamber 4 above the line of liquid. This air may be supplied in a compressed state by a pump through the

valve 20, or it may be supplied by the piston itself in the following manner. Under load conditions the piston will be at the lower end of its stroke. The cap 6 may be unscrewed and a predetermined volume of liquid poured into the cylinder 1 upon the top of the piston 2. The cap 6 is then replaced. Due to the motion of the moving members between which the device is connected, the 10 check valve 17 will operate as a pump allowing the liquid to be displaced from above the piston to a position beneath the same. This causes the air in the chamber 4 to be compressed to a small volume, and a larger 15 quantity of the liquid will enter the chamber 4 through the ports 10 and remain below the volume of compressed air. This will allow the piston a long travel on its upward stroke and the air will thus be compressed 20 in the cylinder 1 above the piston 2. This air when compressed to a sufficient degree to overcome the pressure of the air in the chamber 4 and the tension of the spring 18 of the check valve 17 will open said valve and 25 pass beneath the piston 2. On the succeeding down stroke of said piston this air so entrapped beneath the same will be carried to the ports 10 where it will pass into the chamber 4, adding to the air already contained therein and displacing some of the liquid in said chamber into the cylinder 1. The addition of this amount of liquid in the cylinder 1 will shorten the upstroke of the piston 2, so that on the succeeding upstroke 30 of the piston a smaller volume of air will be passed from the upper to the lower side of said piston. This air is in like manner transferred into the chamber 4 and the upstroke of the piston still further shortened. 35 This action continues until sufficient air has been pumped into the chamber 4. The upstroke of the piston will then be so shortened that it will be unable to compress the air above the piston 2 sufficiently to operate the 40 check valve 17. When this condition is reached the device has been fully charged and its operation is then the same as though the compressed air had been admitted to the chamber 4 from an external source. 45

50 When operating as a resilient device the forces acting upon the piston rod 3 cause the piston 2 to move downward in the cylinder 1 thus forming the liquid through the ports 10 into the chamber 4 and further compressing the air entrapped therein. At the 55 lower end of its stroke the piston 2 gradually covers the ports 10 and due to their shape the orifice is caused to decrease thereby increasing the friction of the liquid in passing from the cylinder 1 to the chamber 4. This has the very desirable effect of introducing a gradual and positive damping action to the motions of the moving member. When the forces acting on the moving member 60 are reduced the pressure of the air in the

chamber 4 causes the liquid to flow therefrom through the ports 10 into the cylinder 1 and return the piston to its original position. The tendency of the moving member to travel past its original position is here 70 reduced by the friction encountered by the liquid in passing from the chamber 4 to the cylinder 1 through the ports 10 and also, by the compression of the air in the chamber 1 above the piston 2. 75

In the normal operation of this device, it is desirable that a small amount of liquid be allowed to escape past the piston 2 into the cylinder 1 above the said piston. To prevent an accumulation of liquid interfering 80 with the proper motion of the piston 2 the check valve 17 will operate to return the excess liquid from the chamber above the piston to the space below as previously described in the method of charging the device. 85

When the apparatus has been allowed to stand quiescent for a long period the leakage of oil to the chamber above the piston may become excessive, and in an application of 90 the device where it is deemed undesirable to await the return of the liquid in the previously described manner, the apparatus may be provided with a mechanical spring whose function is to support the piston under 95 steady load conditions.

In the operation of charging the device it may be necessary to supply the space above the piston 2 with fresh charges of air and to this end any of the well recognized 100 methods may be employed, as for example the check valve 21 shown in Figs. 1 and 2, or the slotted piston rod 22 shown in Fig. 3, although I do not desire to limit myself to either of these methods. 105

If so desired the apparatus may be made to act as a spring of increasing or decreasing scale by changing the shape of the chamber 4 from that of a cylinder to some other form, as for example, a conical form having 110 a smaller cross-sectional area at the top would give the effect of a spring of increasing scale while a conical form having a larger cross-sectional area at the top would give the effect of a spring of decreasing 115 scale.

Various modifications and changes in the designs, construction and operation of my improved resilient device may be resorted to without departing from, the spirit of the 120 invention or sacrificing any of its advantages.

What I claim as my invention and desire to secure by Letters Patent is:—

1. A resilient device comprising a cylinder, a piston operating therein, a chamber containing liquid upon which entrapped air acts, a check valve in said piston for controlling communication between the upper and lower faces of said piston, and ports of 125 130

communication between said cylinder and said chamber so designed and located as to control recoil of the device by causing a variation of port opening with variation of 5 piston travel.

2. A resilient device comprising a cylinder closed at both ends, a piston operating therein, a chamber containing liquid upon which entrapped air acts, a check valve in 10 said piston controlling communication between the upper and lower faces of said piston, the operation of said check valve being controlled by the difference in the fluid pressure on the upper and lower faces of 15 said piston, and ports of communication between said cylinder and said chamber so designed and located as to control recoil of the device by causing a variation of port opening with variation of piston travel.

20 3. A resilient device comprising a cylinder, a piston operating therein, a chamber containing liquid upon which entrapped air acts, a spring directly supporting said piston, and a check valve in said piston for 25 controlling communication between the upper and lower faces of said piston.

4. A resilient device comprising a cylinder, a piston operating therein, a chamber containing liquid upon which entrapped air 30 acts, a spring directly supporting said piston, a check valve in said piston for controlling communication between the upper and lower faces of said piston, and ports of communication between said cylinder 35 and said chamber so designed and located as to control recoil of the device by causing a variation of port opening with variation of piston travel.

5. A resilient device comprising a cylinder closed at both ends, a piston operating 40 therein, a chamber containing liquid upon which entrapped air acts, a spring directly supporting said piston, and a check valve in said piston controlling communication between the upper and lower faces of said piston, the operation of said check valve be-

ing controlled by the variations in the travel of said piston.

6. A resilient device comprising a cylinder closed at both ends, a piston operating 50 therein, a chamber containing liquid upon which entrapped air acts, a spring directly supporting said piston, a check valve in said piston controlling communication between the upper and lower faces of said piston, the operation of said check valve being controlled by the variations in the travel 55 of said piston, and ports of communication between said cylinder and said chamber so designed and located as to control recoil of the device by causing a variation of port opening with variation of piston travel.

7. In a resilient device, the combination 60 of a fixed member, a movable member for carrying the load, a column of liquid, and a chamber containing entrapped air whose pressure transmitted through said column assists in supporting said load, the channel of said column being automatically restricted 65 in the operation of said device in such manner that said column variably retards movement of said member.

8. In a resilient device, the combination 70 of a fixed member, a movable member for carrying the load, a mechanical spring operating between said fixed and movable members and partially supporting the load, a column of liquid, and a chamber containing entrapped air whose pressure transmitted 75 through said column assists in supporting said load, the channel of said column being automatically restricted in the operation of said device in such manner that said column variably retards movement of said member.

In testimony whereas I, the said EDWARD E. Ross, affix my signature in the presence of two witnesses.

EDWARD E. ROSS.
